UNITED STATES PATENT OFFICE.

JOHN REICHERT, OF RACINE, WISCONSIN.

CALF-WEANER AND THE LIKE.

1,366,099.

Specification of Letters Patent.

Patented Jan. 18, 1921.

Application filed September 30, 1919. Serial No. 327,361.

To all whom it may concern:

Be it known that I, JOHN REICHERT, a citizen of the United States of America, and resident of Racine, Racine county, State of Wisconsin, have invented certain new and useful Improvements in and Relating to Calf-Weaners and the like, of which the following is a specification.

This invention relates to certain improvements in calf weaners and the like; and the objects and nature of the invention will be readily understood by those skilled in the art in the light of the following explanation of the accompanying drawings illustrating what I now believe to be the preferred mechanical expression or embodiment of my invention from among other forms, constructions and arrangements within the spirit and scope thereof.

It is an object of the invention to provide certain improvements in devices applicable to the noses of domestic animals, whether cows, calves or colts, to prevent such animals from grasping and extracting milk from their teats.

The embodiment of the invention is, in whole or in part, characterized by a nose piece or frame that comprises the horns or fingers by which the device is applied to and suspended from the nose, and that also forms laterally projecting or end loops to guard the sides or corners of the mouth to prevent the animal from laterally projecting the tongue and grasping a teat at the side or corner of the mouth, and by a swinging guard or apron plate that depends loosely from said nose piece through the medium of one or more loops of the nose piece and one or more eyes of the plate loosely encircling a bar or bars of such loop or loops, with stop means to limit upward swing of the plate with respect to the nose piece.

With these and other objects in view, my invention consists in certain novel features in construction and in combinations and arrangements as more fully and particularly set forth and pointed out hereinafter.

Referring to the accompanying drawings:

Figure 1, is a perspective view of what I now believe to be the preferred embodiment of my invention.

Fig. 2, is a vertical section on the line 2—2, Fig. 1.

Fig. 3, is a detail perspective with parts

detached, and the apron appearing in dotted lines.

Fig. 4, is a perspective view of a modified form.

In the preferred form, the nose piece 60 carries a pair of coöperating horns or fingers 1, 2, extending upwardly with their free ends curving inwardly toward each other to enter the opposite nostrils; the extremities of the fingers being enlarged and rounded 65 at 1^a to engage the septum of the nose. These fingers constitute the means by which the device is attached to and suspended from the nose, as will be readily understood by those skilled in the art.

One of these fingers, in this instance finger 2, is movable with respect to the other finger so that the nose piece can be opened and closed for attachment to and removal from the animal's nose, and is provided with locking means whereby the nose piece can be held normally locked in operative nose grasping adjustment to retain its operative position.

In the embodiments illustrated by Figs. 80 1-4, the suspending finger 1 forms a rigid or integral part of a frame or body that in connection with the pivoted finger 2, constitutes the nose piece. This frame is composed of usually bowed or curved central longitudinal length 3, at its opposite ends terminating in guard arms or vertical loops 4 that in effect, form opposite-end longitudinal continuations of the body length 3. The ends of the body length 3 extend vertically 85 to form the inner end bars or uprights 4^a of the loops 4, respectively, and the fixed finger 1 is in effect, extended inwardly and upwardly from one of these uprights 4^a and extends inwardly approximately from the 90 upper inner corner of one of the loops 4, say the left hand loop Fig. 1. The inner end bar 4^a of the other projecting end loop 4 terminates in the rounded inner upper corner of its loop. The body of the nose piece, in said 100 embodiments, hence consists of a rigid one piece frame composed of the body length 3, the projecting end loops 4 and the fixed finger 1.

In this instance, the movable finger 2 is 105 composed of a rigid U-shaped piece having an extended lower leg 2^a, forming a shank at its outer end having a transverse threaded screw hole 2^b. The rear side of the body length 3 is formed with a reduced or rab-

100

110

beted portion forming a seat 3^b to receive said shank 2^a, and with a transverse screw hole 3^a to register with the screw hole 2^b so that a removable machine screw 5 can be inserted through hole 3^a from the front to screw into threaded hole 2^b and lock the movable finger against the body length and in operative position. Ribs and complementary grooves 6 can be formed in the meeting 10 sides of the body length and finger shank 2^a and radiating from the screw holes, to lock the finger against rocking on the machine screw, as will be readily understood by those skilled in the art.

15 When the finger is in operative position, the shank thereof longitudinally fits the rear side of the body length 3 and from thence the finger extends upwardly along the rear side of the bar 4^a of the right hand (Fig. 1) 20 loop 4 and inwardly from the upper inner corner thereof. By loosening the screw 5, so that the complementary ribs and grooves 6 can clear each other, the finger 2 can swing down on the screw 5 as an axis and thereby open the suspending fingers for removal from or application to the animal's nose. When applied to the nose, the body length 3 is in front of the animal's nose or muzzle, and hence to guard the animal's 30 mouth against grasping teats from the front, yet while permitting the animal free access to grass and feed, I hang a swinging guard or apron 7, from the nose piece frame or body. In the particular example illustrated, this apron consists of a dished sheet metal plate, in transverse width approximately equal to the length of the nose piece frame and at its upper outer corners pivotally hung from the guard loops 4 of said frame so that the apron can swing freely 40 vertically within certain limits. For instance, I show the lower bars 4^b of the loops 4 approximately straight and in alinement, and the sheet metal of the apron at the upper outer corners thereof formed with tongues bent to form eyes 7^a loosely surrounding said bars 4^b and suspending the apron loosely therefrom.

Means are provided to limit the upward 50 swing of the apron with respect to the nose piece to prevent the calf throwing the apron up and back so as to project his tongue forward under the apron and grasp the teat. For instance, in Figs. 1 and 2, I show the nose piece body length 3 at its front side formed with a central forward stop lug or projection 3^c arranged to engage the top edge of the apron and limit its upward swing.

60 In the modification, Fig. 4, I show the apron formed with the stop to engage the front face of the nose piece body length and limit upward swing of said apron. In this modification, the front side of the body length 3 is without lugs or projections, but

the sheet metal apron has a central tongue 7^c projecting up from its front edge to form the stop.

The one piece or rigid nose piece frame 70 enables me to hang the guard apron therefrom at its upper outer corners which is of advantage in that the apron thereby coöperates with the loops 4 in guarding the sides or corners of the calf's mouth, also the eyes 7^a of the apron serve as guards against the upper corners of the apron catching in fence wires, grass and the like, and furthermore the apron hung from both upper corners is held against undue lateral play and tilting and a stable structure is provided. The so loops 4, not only serve as guards but also provide means at both ends of the nose piece frame for easy attachment of the apron without breakage and culls as is the case where cast metal must be bent to form an 85 attaching eye.

It is evident that various changes, modifications and variations might be resorted to without departing from the spirit and scope of my invention and hence I do not wish 90 to limit myself to the exact disclosures hereof.

What I claim is—

1. A weaner comprising a nose piece having central nose grasping fingers pivotally 95 connected whereby said fingers can be opened and closed, said nose piece also having oppositely projecting ends forming guards beyond said fingers, said ends forming loops; and a guard apron at its upper outer corners loosely hung from said loops.

2. A weaner comprising a nose piece consisting of a one piece frame providing longitudinally projecting end guard arms, an intermediate body length and one nose 105 grasping finger, and a separate coöperating nose grasping finger pivotally applied to said body length to swing vertically and provided with securing means.

3. A weaner comprising a nose piece 110 consisting of a one piece frame providing longitudinally projecting end guard arms, an intermediate body length and one nose grasping finger, and a separate coöperating nose grasping finger applied to said body length 115 and provided with securing means; and a depending guard apron at its upper outer corners loosely hung from said guard arms, said body length and apron providing co-operating stop portions to limit relative upward swing of the apron.

4. A weaner comprising a nose piece having nose grasping fingers and opposite end guard loops, and a depending guard apron 125 having tongues at its upper outer corners bent loosely around the lower bars of said loops.

5. A weaner comprising a nose piece having intermediate nose grasping fingers and end loops, and a depending guard apron 130

hung from said loops at its upper outer corners, the central portion of said nose piece having a lug and the central upper portion of said apron formed and arranged to co-
5 operate in limiting the relative upward swing of said apron.

6. A weaner comprising a nose piece having central nose grasping fingers pivotally connected whereby said fingers can be
10 opened and closed, means for locking said fingers in closed adjustment, said nose piece also having oppositely projecting ends forming guards beyond said fingers, said ends forming loops, and a guard apron at
15 its upper outer corners loosely hung from said loops.

7. A weaner comprising a nose piece consisting of a one piece frame providing a central body length having a nose grasping finger projecting therefrom, said frame also having longitudinally projecting end guard arms, a separate coöperating nose grasping finger applied to said body length and arranged for movement toward and
20 away from said first mentioned finger, and a depending guard apron at its outer corners loosely hung from said guard arms.

8. A weaner comprising a nose piece consisting of a one piece frame providing a central body length having a nose grasping finger projecting therefrom, said frame also having longitudinally projecting end guard arms, a separate coöperating nose grasping finger pivotally applied to said body length
35 to swing vertically toward and away from said first mentioned finger.

9. A weaner comprising a nose piece consisting of a one piece frame providing a central body length having a nose grasping finger projecting therefrom, an apron pivot-

ally carried by the nose piece, said frame also having longitudinally projecting end guard arms, a separate coöperating nose grasping finger, said body length and apron providing coöperating stop portions to limit
45 relative upward swing of the apron.

10. A weaner comprising a nose piece consisting of a one piece frame providing a central body length having a nose grasping finger projecting therefrom, said frame also having longitudinally projecting end guard arms, a separate coöperating nose grasping finger pivotally connected to said body length to swing vertically toward and away
50 from said first mentioned finger, means for locking said pivoted finger in closed adjustment, and a depending guard apron at its upper outer corners loosely hung from said guard arms.
55

11. A weaner comprising a nose piece having nose grasping fingers, a pivotal connection between said fingers whereby the latter may be opened and closed, coöperating means upon said fingers at said connection for releasably maintaining said fingers in
60 closed position, a guard apron pivotally carried by the nose piece, and said apron and nose piece providing coöperating stop portions to limit relative upward swing of the apron.
70

12. A weaner comprising a nose piece having intermediate nose gripping fingers and end guard loops, a guard apron, means formed from the body portion of said guard apron whereby the same is loosely mounted
75 on and swingably depends from said nose piece, and said nose piece and guard apron arranged to coöperate in limiting the relative upward swing of said apron.

JOHN REICHERT.
